LIFT TRUCK

Tom P. Simovich, Arcadia, Calif., assignor to Champ Corporation, El Monte, Calif., a corporation of California

Filed July 30, 1963, Ser. No. 76,041

Term of patent 14 years

(Cl. D14—3)

FIG. 1

Des. 198,366

FIG. 2

FIG. 1 is a front perspective view of a lift truck showing my new design;

FIG. 2 is an enlarged rear perspective view thereof; and

FIG. 3 is a perspective view of the right side and front thereof with the canopy removed.

The side of the lift truck which is not shown has substantially the same appearance as the side which is shown, and the dominant features of the design reside in the portions shown in full lines.

I claim:

The ornamental design for a lift truck, substantially as shown and described.
